Specification of Letters Patent.

Patented Jan. 9, 1917.

Application filed July 18, 1916. Serial No. 109,937.

To all whom it may concern:

Be it known that we, THEODORE FRANK KOTTER, a resident of the borough of Manhattan, city, county, and State of New York, 5 RICHARD VAN CLEEF COLTON, a resident of the borough of Richmond, county of Richmond, city and State of New York, and SIGMUND HARRY SCHWERIN, a resident of the borough of Brooklyn, county of Kings, 10 city and State of New York, citizens of the United States, and residents as above set forth, have invented certain new and useful Improvements in Ornamenting Surfaces, of which the following is a specification.

15 In this application and in the description which follows we will set forth a method for producing designs on surfaces, and particularly upon flexible surfaces.

In our experiments and in the work which 20 has resulted therefrom, we have operated with such flexible surfaces as felt and woven fabrics and although we are fully aware that our method may be employed in decorating other materials we will throughout 25 the specification, refer to it as employed in the decoration of felt.

Because of the peculiar nature of felt it 30 has been found difficult to apply to the surface thereof painting, printed or embossed designs, for the reason that embossing does not permanently shape the felt to an extent sufficient to allow it to retain the design and in painting or printing the ink or paint spreads beyond the confines of the design. 35 and therefore the appearance of the finished product is neither artistic nor satisfactory.

In our method of operation we employ a 40 peculiar base or adhesive applied in a peculiar manner and into or upon the adhesive we place the decorative material which will later be treated in a desirable manner.

The result of our method of operation and the advantages to be gained therefrom will 45 be fully described as the specification progresses.

The following is what we consider the best means of carrying out this invention and the accompanying drawings should be referred to for a better understanding of 50 the description which follows.

In the drawings: Figure 1 shows a pattern bearing member. Fig. 2 a small section of felt after the adhesive has been ap-

plied. Fig. 3 a similar section after the beading has been applied to the adhesive. 55 Fig. 4 a tinted portion from which the beading was omitted.

Similar reference numerals indicate like parts in all of the figures where they appear. 60

In operating according to our method we select a piece of foraminous gauze such as bolting cloth, milling cloth or any other screen of comparatively fine mesh. Upon the gauze or screen we outline a desirable 65 pattern or figure as indicated at 1, and then to the surface of the gauze, exterior to the outline of the pattern we apply water-proof varnish or paint, of such a nature and to such a thickness as will entirely close the 70 openings in the screening exterior to the outline of the pattern, though it is desirable that the varnish or paint be of such a nature that it will not become brittle, but will allow the gauze to retain its flexibility. 75 The surface 2, in Fig. 1, is shown as treated with a suitable varnish. When the varnish is dry the pattern bearing member is ready for use, we then prepare or obtain a suitable adhesive, one that may be operated in 80 a plastic form that will have a desirable amount of viscosity and one that will not become hardened when dry, for as our decoration is applied to flexible surfaces, we desire that the adhesive should also be permanently flexible. 85

A member to be decorated is placed under the pattern bearing member and then by means of a pouncet, the adhesive is forced through the pattern bearing portion or the 90 unvarnished portion of the foraminous gauze on to or upon the surfaces under the pattern bearing member. After this operation it will be found that the felt or other surfaces to be decorated has received a quantity of adhesive sufficient to imprint upon the surface the unvarnished pattern 3. Shortly after the adhesive has been applied as described a quantity of glass beads 4, sometimes termed pearls, flitters or frosting 100 is applied onto the adhesive, but this we have not found entirely necessary. The beaded surfaces is then allowed to dry and when fully dried it may be tinted or colored by means of a hand brush, or air brush or 105 by any other suitable means and to produce

any desirable effect, and by means of the method described flower or other figures may be transferred in their natural colors with great rapidity and at a low cost.

5 In a certain and less complete development of the invention we may omit the glass beads or flitters and may allow the adhesive to dry and later tint it as shown in Fig. 4.

Wherever the glass beads are used we take 10 especial care to see that the coloring matter applied thereto is semi-transparent and thin so that the opalescence of the glass will not be destroyed. Further it is important that different portions of a design be colored according 15 to the requirements to produce a naturally appearing product. Solid colors should not be used, as they destroy the artistic effect. It is further important that the glass be applied at the time that the adhesive is sufficiently dry to have a maximum viscosity and that certain portions of the pattern member within the outline of the design should be varnished or painted to allow none of the adhesive to pass there-through as a lack of continuity of the adhesive adds to the flexibility of the finished product.

The use of a gauze in our method of operation is not merely for the purpose of a pattern bearing member, for if this were its 30 only purpose an ordinary cut stencil might be employed, but we have found that by forcing the adhesive through a gauze of fine mesh by means of a pounce, the adhesive is split up or subdivided and is applied in a somewhat granular form. This 35 sub-division of the adhesive adds materially to the flexibility of the finished product and allows the adhesive and the material 40 added thereto to be retained upon the flexible surface to which it is applied, even though that surface is bent at a sharp angle or rolled or roughly handled.

It is hardly possible to discover that the 45 adhesive is granulated or sub-divided during an application, as when the beading or coloring matter is applied a finished product

has every appearance of the complete and integrally formed surfaces.

The tinting of the coloring matter should 50 be thin not only to preserve the shape and brilliancy of the beading as described, but so that it may pass beyond the beads and be received by the surfaces to which the beading is attached.

55 We prefer the use of an adhesive containing oil and white-lead, and a small quantity of zinc, as such an adhesive will not destroy the brilliancy of the beads but will also be more permanent than the more ordinary 60 glues or pastes.

Having carefully and fully described our invention what we claim and desire to secure by Letters Patent is:

1. The method of decorating surfaces 65 which consists of applying to the surfaces a finely subdivided adhesive inserting particles of glass into said adhesive and applying to said particles of glass and adhesive a semi-transparent tint which will allow the 70 glass to shine therethrough.

2. The method of decorating surfaces consisting in placing upon the surface to be decorated a foraminous pattern bearing member forcing an adhesive through the interstices of said foraminous member and applying particles of glass to said surface and tinting said glass particles with thin coloring matter that will not conceal the surface of the glass as herein specified.

80 3. The method of decorating flexible surfaces which consists of forcibly applying to the surface to be decorated an adhesive, inserting into said adhesive material having a hard and brilliant surface and when the adhesive is dry applying to the exposed part 85 of said brilliant surface a semi-transparent tint through which the brilliancy of the surface may be observed.

Dated New York city, New York, July 90
8, 1916.
